UNITED STATES PATENT OFFICE.

ORANGE O. OZIAS, OF DAYTON, OHIO, ASSIGNOR TO THE COMPUTING SCALE COMPANY, OF OHIO.

DESIGN FOR A SCALE-SUPPORT.

SPECIFICATION forming part of Design No. 32,006, dated December 19, 1899.

Application filed October 30, 1899. Serial No. 735,325. Term of patent 7 years.

To all whom it may concern:

Be it known that I, ORANGE O. OZIAS, of Dayton, in the county of Montgomery and State of Ohio, have produced a new and original Design for a Scale-Support, of which the following is a specification, reference being had to the accompanying drawing, forming part thereof, in which like figures refer to like parts.

10 The figure in the drawing illustrates a perspective view of a scale-support embodying my invention and design.

15 My invention and design for a scale-support consists, essentially, of a substantially rectangular base having two uprights projecting from near one end thereof and two projections extending upwardly from near the opposite end of said base.

In said drawing, 10 represents said substantially rectangular base, 11 and 12 represent the two uprights projecting from near one end of said base 10, and 14 and 15 represent the two projections extending upwardly from near the opposite end of said base. 16 represents an opening through the top of said base.

What I claim is—

The design for a scale-support substantially as shown and described.

In witness whereof I have hereunto set my hand this 10th day of October, 1899.

ORANGE O. OZIAS.
